Primary Examiner — Amy C Wierenga*Assistant Examiner* — Kathryn Elizabeth Zieno(74) *Attorney, Agent, or Firm* — Michael A DiNardo; Iain Hill; YK Law, LLP(57) **CLAIM**

The ornamental design for a floating pool filter cup, as shown and described.

DESCRIPTION

FIG. 1 is top front perspective of the floating pool filter cup; FIG. 2 is a bottom rear perspective of the floating pool filter cup from the reverse angle of FIG. 1; FIG. 3 is a front elevation of the floating pool filter cup; FIG. 4 is a rear elevation of the floating pool filter cup; FIG. 5 is a left elevation side of the floating pool filter cup (the right side view is a mirror image); FIG. 6 is a top plan of the floating pool filter cup; and, FIG. 7 is a bottom plan of the floating pool filter cup. The dashed broken lines depict portions of the floating pool filter cup that form no part of the claim. The stippled shading represents a contrast in appearance.
